UNITED STATES PATENT OFFICE

162,155

MEDAL FOR RELIGIOUS USE

Henry H. Gray, Seattle, Wash.

Application August 8, 1949, Serial No. 4,351

Term of patent 14 years

(Cl. D29—19)

To all whom it may concern:

Be it known that I, Henry H. Gray, a citizen of the United States of America, residing at Seattle, in the county of King and State of Washington, have invented a new, original, and ornamental Design for a Medal for Religious Use, of which the following is a specification, reference being had to the accompanying drawing, forming part hereof.

Fig. 1 is a view of the identical obverse and reverse faces of the medal for religious use, illustrating my design; and.

Fig. 2 is an edge view of the same.

The dominant features of my design reside in the portions shown in full lines.

I claim:

The ornamental design for a medal for religious use, substantially as shown and described.

HENRY H. GRAY.
